UNITED STATES PATENT OFFICE.

GEORGE WILLIAM ERICSON, OF GALESBURG, ILLINOIS.

MARKER.

1,375,685.

Specification of Letters Patent. Patented Apr. 26, 1921.

Application filed September 2, 1920. Serial No. 407,678.

To all whom it may concern:

Be it known that I, GEORGE W. ERICSON, a citizen of the United States, residing at Galesburg, in the county of Knox and State 5 of Illinois, have invented a new and useful Marker, of which the following is a specification.

It is the object of this invention to provide a simple and inexpensive but efficient 10 means whereby a card or plate may be held on an umbrella, a cane or other article of a like sort.

It is within the province of the disclosure to improve generally and to enhance the 15 utility of devices of that type to which the invention appertains.

With the above and other objects in view, which will appear as the description proceeds, the invention resides in the combination 20 and arrangement of parts and in the details of construction hereinafter described and claimed, it being understood that, within the scope of what is claimed, changes in the precise embodiment of the invention 25 shown can be made without departing from the spirit of the invention.

In the accompanying drawings:—

Figure 1 shows in plan, the blank from 30 which the marker is formed; Fig. 2 is a perspective view showing the marker in partially completed condition; Fig. 3 is a transverse section; Fig. 4 is a perspective showing the marker applied to a cane, the line 3—3 of Fig. 4 denoting the plane on 35 which Fig. 3 is cut; and Fig. 5 is a plan of the marker, laid flat, the card being in place.

The marker forming the subject matter of this application is made from a plate 1 provided adjacent to one longitudinal edge 2 40 with openings 3, there being reduced tongues 5, 6 and 7 projecting from the opposite longitudinal edge 4 of the plate. Fingers 8 outstand from the plate 1 at the ends thereof, in alignment with an elongated aperture 9 fashioned in the plate relatively near 45 to the edge 2.

A card or the like, indicated at 10, may be

placed against the rear face of the plate 1, the fingers 8 being bent inwardly to engage the card at its ends, as shown in Fig. 50 5. The plate 1 is bent to form a flat body 11 and a bendable wing 12, the tongues 5, 6 and 7 being received in the openings 3. Since the tongues are of different lengths, the tongues may be inserted into the openings 3, one at a time, the operation of inserting the tongues into the openings being facilitated accordingly. The device, by the operation above alluded to, may be held about a cane 14 or other article. As indicated in Fig. 3 of the drawings, those portions of the wing 12 which are adjacent to the body 11, are disposed substantially at right angles to the body, as denoted by the numeral 15. A card 10 may be retained by 60 the fingers 8 on the body 11 so that the card is visible through the aperture 9. The portions 15 serve to retain the card 10 in the fingers 8 and prevent the card from sliding out of the fingers, longitudinally of the 70 fingers.

Having thus described the invention, what is claimed is:—

A marker fashioned from a plate disposed in tubular form and provided adjacent to 75 one longitudinal edge with a plurality of openings, and provided along its opposite longitudinal edge with reduced tongues received in the openings and clenched on the plate, the tongues decreasing successively in 80 length to facilitate the insertion of the tongues one at a time into the openings, the plate being equipped at its ends with inwardly projecting card holding fingers, there being an aperture in the plate, between the 85 fingers, adapted to disclose a card held in the fingers.

In testimony that I claim the foregoing as my own, I have hereto affixed my signature in the presence of two witnesses.

GEORGE WILLIAM ERICSON.
